Int. Cl. D21—01

U.S. Cl. D34—5

FIG. 1

FIG. 2

FIG. 3

FIG. 1 is a top plan view of my spinning indicator device;

FIG. 2 is a side elevational view thereof, with the spinner disposed normal to the line of vision; and

FIG. 3 is a side elevational view thereof, with the spinner disposed parallel to the line of vision.

Side elevational views taken from other points of vantage are essentially the same as that shown in FIG. 2. The bottom is plain, circular, and flat.

I claim:

The ornamental design for a spinning indicator device, as shown and described.
